UNITED STATES PATENT OFFICE.

ERIC MONTAGUE SMITH, OF SALTFORD, ENGLAND.

VALVELESS HYDRAULIC APPARATUS.

Application filed May 19, 1922. Serial No. 562,050.

To all whom it may concern:

Be it known that I, ERIC MONTAGUE SMITH, residing at Keynsham Manor, Saltford, in the county of Somerset, England, a 5 subject of the King of Great Britain, have invented certain new and useful Improvements in or Relating to Valveless Hydraulic Apparatus, of which the following is a specification.

10 This invention refers to improvements in valveless hydraulic apparatus or presses applicable for use in connection with various apparatus such as, for example, metal punching, shearing or cropping machines or 15 the like wherein hydraulic pressure is employed to act in conjunction with and to amplify mechanically obtained pressure; and one of the objects of my present invention is to provide an improved and simplified apparatus in which, amongst other features, is provided novel means for effecting a positive retraction of the hydraulic ram after a power stroke.

20 Valveless hydraulic apparatus according 25 to this invention comprises two co-axial cylinders of different bore arranged in prolongation of, and freely open to each other, to form a common space for the hydraulic fluid, a liquid-tight ram operating within 30 the larger bore, a liquid tight plunger operating within the smaller bore, means for positively retracting the ram after a working stroke, and means for reciprocating said plunger.

35 Details of the construction and operation of my improved hydraulic press will be more fully described with reference to the drawings which illustrate by way of example, only a valveless hydraulic press according 40 to my invention applied to a punching machine, although it is to be understood that my valveless hydraulic press apparatus may be employed in connection with any machine or for any purpose to which such press 45 may be applicable.

Fig. 1 is a view in side elevation partly 50 in section on the line 1—1 of Fig. 2 of a punching machine according to my present invention with the lever pulled fully down and the plunger and the ram at the extreme end of the downward punching stroke.

Fig. 2 is an end elevation of Fig. 1 partly 55 in section on the line 2—2 of Fig. 1.

Fig. 3 is a side elevation partly in section of an alternative construction according to my present invention the various modifica-

tions in which will be hereinafter described in detail.

Fig. 4 shows a local longitudinal section through the ram cylinder illustrating an alternative construction of the ram in which the upper surface thereof is recessed or cut away in suchwise as to produce an obturating effect on the upper outer circumference of the ram when pressure is applied, thereby to prevent leakage of oil past the ram.

In Figs. 1 and 2:—

A is the cylinder of differential bore, A¹ that portion of the cylinder in which the 70 ram B is adapted to be reciprocated this said cylinder A¹ being hereinafter referred to as the "ram cylinder."

A² is the smaller bored portion of the cylinder A provided at its upper end with 75 a gland A³ and designed to receive the plunger C to be reciprocated therein said plunger C being provided at its lower end with an hydraulic cup ring C¹, the upper end of the plunger C being closed by a lead 80 washer C² over which latter a metal cap is screwed down.

The bushing C⁴ screwed into the lower end of the plunger C provides a seating or stop for the enlarged head D¹ of the "ram 85 withdrawing rod" D, the lower end of which latter is screwed into the top of the ram B.

The ram B is cut away to provide an oil space E and is provided with an hydraulic cup ring F to make a tight fit with the ram 90 cylinder A¹.

A filling hole E¹ is provided in the ram cylinder A¹ for the admission of oil or other desired fluid and is closed by the screw-threaded cap E² (see Fig. 2). 95

A set screw B¹ fitting in the longitudinal slot or recess B² in the ram B is screwed through the cylinder A¹ to prevent rotation of the ram B when in use (see Fig. 2).

The ram B is recessed in the underside 100 for the reception of the punch G and a set screw G¹ is screwed transversely into the ram B to hold the punch or other desired tool in position a recess G² being provided in the shank of the punch for the purpose 105 of receiving the end of the set screw G¹.

A stripper plate H is mounted on the rod H¹ by means of the locking screw H² and the rod H¹ being fixed at its upper end to the ram cylinder body A its forked ends embracing the punch G for the purpose of stripping therefrom the work-piece when the punch is 110

returning to normal position after a punching operation.

- The cylinder A is formed with a lateral extension A⁴ adapted to be received in a recess 5 J² in the upwardly extending bracket J¹ of the base J of the machine, this projecting portion A⁴ being centrally bored and internally screw-threaded to receive a corresponding screw-threaded fixing bolt K.
- 10 A die-plate L is provided with a series of holes or openings therethrough of different sizes (or/and if desired of different shapes) arranged equidistant from a common centre on said plate; and this die-plate L is mounted 15 or carried on a central pin or spindle L¹ adapted to be revolvably mounted in a suitable recess J⁴ in the base J.

The die plate L is mounted eccentrically with respect to the punch G on the ram B 20 so that whatever sized or shaped punch may be mounted on the ram the die-plate can be revolved to bring the corresponding hole below said punch and then the die-plate locked in this position by tightening set 25 screws (not shown) in the transverse screw-threaded borings J³ J⁵ in the base J.

The lever N is pivotally attached to the metal cross-head C³ on the plunger C and is also pivotally attached at M² to the links M 30 which in turn are pivotally mounted at M¹ on the bracket J¹, the whole being so arranged and proportioned that the thrust on the plunger C is purely vertical when the lever N is operated.

35 Fig. 3 illustrates an alternative construction wherein a cylindrical metal sleeve O is fixedly mounted on or formed integral with the bracket J¹, this sleeve O being internally screw-threaded for a portion of its length 40 and adapted to receive the ram cylinder A¹ which is correspondingly screw-threaded externally, the whole hydraulic mechanism being thereby capable of vertical adjustment relative to the base of the machine.

45 An internally screw-threaded locking ring P is provided to lock the cylinder A¹ in any position to which it has been so adjusted.

In this construction the plunger cylinder A² is extended downwardly into the ram cylinder A¹ and the top of the ram is centrally recessed or cut away, if desired.

50 Fig. 4 illustrates a modified construction of the ram B the upper portion of which in this case is recessed or cut away in suchwise as to leave a relatively thin and upwardly tapering wall B¹ for the purpose of producing an obturating effect in the ram cylinder when pressure is applied, thereby to assist in ensuring against leakage of oil past the ram 55 in operation.

The operation is as follows:—

When the lever N² N is pulled down the plunger C is thereby forced downwardly in the plunger cylinder A² forcing the oil or 60 other liquid therein into the oil space E in

the larger part A¹ of the cylinder which is already quite full of liquid, the ram B carrying the punch G or other tool being thereby powerfully driven down towards the work-piece.

70

The lever N² N is designed according to the leverage required, i. e. to the power to be transmitted to the plunger C; and the length of travel to be imparted to the plunger C is also designed according to the 75 stroke or travel to be thereby imparted to the ram B, e. g. with a leverage of 10 to 1 exerted on the plunger C and the area of the end of the plunger C one-tenth the area of the ram B, then with a 100 lb. pull at the end of the lever N² N a pressure of approximately 10,000 lbs. would be exerted on the punch G or other tool fixed to the ram.

80

When the punching or other action has been effected the lever N² N is drawn back 85 until the enlarged head end D¹ of the ram withdrawing rod D is engaged by the seating formed by the bushing C⁴ in the bore of the plunger C and upon the lever being returned to normal position the ram withdrawing rod D is thereby carried upwardly bringing back into normal position the ram B to which the lower end of the ram withdrawing rod D is fixed at the same time stripping the 90 work-piece from the tool ready for the next punching or other operation.

95

The diameter of the enlarged head D¹ of the ram withdrawing rod D is smaller than the diameter of the bore of the plunger C to thus permit the passage of the oil past this head D¹ during relative movement of said plunger C and rod D; while the said rod D where it passes through the lower end of said plunger C makes only a loose fit with said lower end or the interior wall of the bushing C⁴—through which the rod D slides—may be provided with vertical grooves or channels, so as to allow the passage of oil between the interior of the plunger C and the oil space E.

100

105 A recess J⁴ is provided in the base J for withdrawing the punchings or cuttings or permitting them to drop; said slot J⁴ being vertically disposed in said fixed base J and extending from the interior of the side wall to the centre of the seating for the die-plate L or other work-piece support, in suchwise that a pin or stud centrally fixed on the under surface of the die-plate or the support for the work-piece may be slid along and completely out of said slot thereby to remove 110 the die-plate or work-piece support.

115

When it is desired to alter the diameter of the punch it is only necessary to slacken the screws J³ holding the work-piece support in position, revolve the support (such as the die-plate L hereinbefore described) until the hole of the desired diameter is directly under the punch G and again tighten the screws J³; the screw H² retaining the stripper plate H is then loosened, the strip- 120

125

120

per plate removed and a punch of the required size substituted in the ram head and the stripper plate H then re-fixed.

It is understood that the valveless hydraulic mechanism according to my present invention which I have herein described and illustrated as applied to a punching tool may be employed in conjunction with any other tool or machine to which it is or may be applicable.

For example it is applicable to and may advantageously be employed in such processes as shearing, cropping, rivetting, embossing, piercing, bar straightening and the like.

What I claim is:—

1. Valveless hydraulic apparatus comprising two co-axial cylinders of different bore, arranged in prolongation of, and freely open to, each other to form a common space for the hydraulic fluid, a liquid-tight ram operating within the larger bore, a hollow liquid-tight plunger operating within the smaller bore, a shoulder formed within the lower end of said plunger, a ram-retracting device comprising an inextensible member attached at one end to the ram and having an enlargement sliding loosely within said hollow plunger and adapted to be engaged by the shoulder within said plunger towards the end of the return stroke of the latter and means operatively connected to said plunger to actuate same.

2. Valveless hydraulic apparatus comprising two co-axial cylinders of different bore, arranged in prolongation of, and freely open to, each other to form a common space for the hydraulic fluid, a liquid-tight ram oper-

ating within the larger bore, a hollow liquid-tight plunger operating within the smaller bore, a shoulder formed within the lower end of said plunger, a ram-retracting device comprising an inextensible member attached at one end to the ram and having an enlargement sliding loosely within said hollow plunger and adapted to be engaged by the shoulder within said plunger towards the end of the return stroke of the latter and means operatively connected to said plunger to actuate same.

3. Valveless hydraulic apparatus comprising two co-axial cylinders of different bore, arranged in prolongation of, and freely open to, each other to form a common space for the hydraulic fluid, a liquid-tight ram operating within the larger bore, a hollow liquid-tight plunger operating within the smaller bore, a shoulder formed within the lower end of said plunger, a ram-retracting device comprising an inextensible member attached at one end to the ram and having an enlargement sliding loosely within said hollow plunger and adapted to be engaged by the shoulder within said plunger towards the end of the return stroke of the latter, and a system of levers connected to said plunger and to the base of the apparatus in suchwise as to exert axial thrust upon said plunger to actuate the same.

ERIC MONTAGUE SMITH.
